(57) **CLAIM**

The ornamental design for a square transition bottle with round base, as shown and described.

DESCRIPTION

FIG. 1 shows a top-facing perspective view of a square transition bottle with round base, showing my new design; FIG. 2 shows a bottom-facing perspective view thereof; FIG. 3 shows a front elevation view thereof; FIG. 4 shows a rear elevation view thereof; FIG. 5 shows a left rotated elevation view thereof; FIG. 6 shows a right rotated elevation view thereof; FIG. 7 shows an enlarged top plan view thereof; FIG. 8 shows an enlarged bottom plan view thereof; and, FIG. 9 shows an environment of use thereof. The broken lines indicate unclaimed aspects of the square transition bottle with round base or environment and form not part of the claimed invention. The broken lines depicting two bottles in FIG. 9 illustrate environmental structure that form not part of the claimed design.
